Primary Examiner — Elizabeth J Oswecki(74) *Attorney, Agent, or Firm* — Nath, Goldberg & Meyer;
Jerald L. Meyer; Scott C. Langford(57) **CLAIM**

The ornamental design for a reindeer cork cage ornament, as shown and described.

DESCRIPTION

FIG. 1 is a perspective view of a reindeer cork cage ornament showing my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top view thereof; and,

FIG. 7 is a bottom view thereof.

The broken lines shown in the drawings represent portions of the reindeer cork cage ornament that form no part of the claimed design.
